UNITED STATES PATENT OFFICE.

THOMAS HALEY, OF PHILADELPHIA, PENNSYLVANIA.

VALVE-GUARD FOR GAS-STOVES.

No. 856,057.

Specification of Letters Patent.

Patented June 4, 1907.

Application filed March 26, 1907. Serial No. 364,742.

To all whom it may concern:

Be it known that I, THOMAS HALEY, a citizen of the United States, residing in the city and county of Philadelphia, State of Pennsylvania, have invented a new and useful 5 Valve-Guard for Gas-Stoves, of which the following is a specification.

In gas stoves constructed under present methods, there is always a liability of the 10 valve being opened or left open by mistake, and especially where there are small children around, it has been found that the valves are often partially opened by them, thus permitting the gas to escape and rendering possible 15 an explosion with consequent loss, and damage.

The object of my present invention is to devise a novel construction of a valve protecting member which is adapted to be 20 readily placed in position on any desired type of gas stove, heater or the like having gas pipes leading thereto, and by the employment of which any inadvertant or careless opening of any of the valves is positively 25 prevented.

To the above ends my invention broadly consists in a novel construction of a plate which is automatically locked in position when the same is placed on the gas stove.

30 It further consists of a novel construction of plate, the upper surface of which is deflected so as to form a flush surface with the top of the gas stove and the lower portion of which is provided with angular slots adapted to co-act with the branches leading from the main feed pipe.

It further consists of a novel construction and correlation with the above mentioned plate, of a locking pawl which is carried by 40 the valve guard and prevents any improper movement of the same when placed in position.

It further consists of a novel construction 45 of a valve guard having angular shaped slots therein, provision being made whereby the valve guard must be moved in a plurality of directions before the same is disengaged from the branch feed pipes in order that the valve guard will not be tampered with or improperly removed by children or others.

50 It further consists of other novel features of construction, all as will be hereinafter fully set forth.

For the purpose of illustrating my invention I have shown in the accompanying drawings 55 one form of a device, since this embodiment has been found in practice to give satisfactory and reliable results, although it is to be understood that the various instrumentalities of which my invention consists may be 60 variously arranged and organized and that my invention is not limited to the precise arrangement and organization of these instrumentalities as herein shown.

Figure 1 represents a perspective view of a 65 valve guard embodying my invention. Fig. 2 represents a side elevation of a portion of a gas stove having a valve guard embodying my invention in operative relation therewith. Fig. 3 represents an end elevation of 70 a portion of a gas stove, the valve guard, main feed pipe and valve lever being shown in section. Fig. 4 represents a side elevation of a valve guard showing a modified form of a locking recess.

75 Similar numerals of reference indicate corresponding parts in the figures.

Referring to the drawings:—1 designates a gas stove of any usual or conventional type and having preferably an off-set 2 at the front 80 end thereof.

3 designates the main feed pipe which is supported, in the present instance by the hangers 4 carried by the gas stove 1.

5 designates branch pipes leading from the 85 main feed pipe 3 to the burners (not shown).

6 designates my novel construction of valve guard which, in the present instance comprises a plate 7, the upper end of which is deflected as seen at 8 in a substantially horizontal plane so that it forms a flush surface with the top of the stove as is clearly indicated in Fig. 3.

9 designates a series of slots angularly inclined to the bottom of the plate, from which 95 extend angular slots 10, it being noted that the number of these communicating slots 9 and 10 depends upon the number of branch feed pipes 5 which are employed. The extensions 11 formed by the slots 9 are rounded 100 on their under side, as is clearly indicated at 12, in Figs. 1 and 2. The vertically extending portion of the plate 7 has its end cut away as indicated at 13 and 14 in order that the plate may pass between the hangers 4 and 105 have longitudinal movement therebetween,

it being noticed that in the present instance the cut away portion 14 is of greater extent than the cut away portion 13, so that the shoulder 15 formed by the cut away portion 13 will abut against the hanger 4 contiguous thereto when the valve guard is moved to the right.

16 designates a handle of any desired type secured in proximity to one end of the valve guard 6.

17 designates a locking pawl, the outer end of which is pivoted at 18 to the plate 7, said pawl having fixed thereto a suitable handle 19, the pin of which co-acts with the cam slot 20 in the plate 7, as is clearly apparent from Figs. 1 and 2. The pawl 17 is provided on its under side with a face 21 from which extends angularly a face 22 so that when the pawl 17 is permitted to assume its lowermost position 20 said face 22 will engage one of the hangers 4.

In order to prevent, in a more positive manner, any improper removal of the valve guard 6, it is advantageous under some conditions to employ a slot such as is shown in the embodiment seen in Fig. 4, in which the slot 10 has communicating therewith on its upper side, a recess 23 preferably having a semi-cylindrical contour in order that the wall of the recess 23 will closely engage the branch feed pipe 5. The branch feed pipes 5 have located therein a valve 24 of any desired type.

The operation of my device will now be readily apparent: When it is desired to place the valve guard in position the operator lifts the same by means of the handles 16 and 19 and brings it into such a position that the slots 9 register with the branch feed pipes 5. The valve guard is permitted to descend until the branch feed pipes engage the slot 10, whereupon the valve guard is moved to the right. The operator now releases the handles 16 and 19 and when the handle 19 is released it will fall of its own weight so that the face 22 will closely engage one side of the hanger 4, it being apparent that the wall 15 of the valve guard will closely engage the opposite side of said hanger. It will be apparent that when a valve guard embodying my invention is in position that all of the valves 24 will be concealed and that it will be impossible to open these valves until the valve guard is removed, which is done by grasping the handles 16 and 19 and moving the valve guard to the left until the slots 9 register with the branch feed pipes 5, whereupon the valve guard may be readily removed, as will be apparent to those skilled in the art. In order that the valve guard may be more easily placed in position 60 the under side of the same contiguous the slots 9 is preferably rounded.

It will now be apparent from the foregoing that I have devised a novel and useful con-

struction of valve guard for gas stoves which embodies the features of advantage enumerated as desirable in the statement of invention and the above description and while I have in the present instance shown and described the preferred embodiment thereof which has been found in practice to give satisfactory and reliable results, it is to be understood that the same is susceptible of modification in various particulars without departing from the spirit and scope of the invention or sacrificing any of its advantages.

Having thus described my invention, what I claim as new and desire to secure by Letters Patent, is:—

1. A valve guard for gas stoves comprising an integral piece of metal having angular shaped slots in the bottom thereof, and means carried by said member for preventing improper movement thereof when in assembled position.

2. A valve guard comprising an integral member having its upper end deflected and its lower end provided with a series of angular shaped slots, and means carried by said member for preventing improper movement thereof when in assembled position.

3. A valve guard for gas stoves comprising a plate having its upper end deflected and having at its lower end a series of angular shaped slots, a pawl pivoted to said plate, said plate having a cam slot therein, and means carried by said pawl and co-acting with said slot to guide the movement of said pawl.

4. In a device of the character described, the combination with a main feed pipe and valved feed pipes leading therefrom, of a valve guard comprising a plate having angular shaped slots in its lower portion adapted to co-act with said valved feed pipes to conceal the valves thereof.

5. In a device of the character described, the combination with a main feed pipe and valved feed pipes leading therefrom, of a valve guard comprising a plate having angular shaped slots in its lower portion adapted to co-act with said valved feed pipes to conceal the valves thereof, and means carried by said plate for preventing its improper movement with respect to said feed pipes.

6. In a device of the character described, the combination with a main feed pipe and valved feed pipes leading therefrom, of a valve guard comprising a plate having angular shaped slots in its lower portion adapted to co-act with said valved feed pipes to conceal the valves thereof, and handles carried by said plate for manually actuating the same.

7. In a device of the character described, the combination with a gas stove, the main feed pipe thereof, hangers supporting said feed pipe, and valved feed pipes leading from

said main feed pipe, of a valve guard comprising a plate having angular shaped slots adapted to co-act with said valve feed pipes, said plate having its ends recessed to permit 5 longitudinal movement thereof with respect to said hangers, and locking means carried by said plate and co-acting with one of said

hangers to prevent improper relative movement of said plate and hangers.
